INTERDENTAL WEDGE OR SIMILAR ARTICLE

Carl-Johan Sjodahl, Örebro, Sweden, assignor to
Dentalvarutjanst AB, Örebro, Sweden

Filed Oct. 9, 1974, Ser. No. 513,936

Claims priority, application Sweden May 3, 1974

Term of patent 14 years

Int. Cl. D24—04

U.S. Cl. D24—1 D

Fig. 1

Fig. 2

Fig. 3

FIG. 1 is a perspective view of an interdental wedge, showing my new design;

FIG. 2 is a perspective as seen from the side opposite FIG. 1; and

FIG. 3 is an end elevation thereof.

I claim:

The ornamental design for an interdental wedge or similar article, as shown.
